(57) **CLAIM**

The ornamental design for an audio and docking station for handheld electronic device, as shown and described.

DESCRIPTION

FIG. 1 is a perspective view of an audio and docking station for handheld electronic device showing my new design;

FIG. 2 is a front elevational view thereof;

FIG. 3 is a side elevational view, the opposite side elevational view being a mirror image thereof;

FIG. 4 is a rear elevational view thereof;

FIG. 5 is a top plan view thereof;

FIG. 6 is a bottom plan view thereof; and,

FIG. 7 is a perspective view illustrating the positioning of a handheld electronic device.

The broken line showings of the rectangular area on the horizontal surface in FIGS. 1 and 5; the diamond-shaped clusters of circles on the front in FIGS. 1, 2, 5 and 7; the four circles on the rear in FIG. 4; and the circles and arc-shaped area on the bottom in FIG. 6 are for illustrative purposes only and form no part of the claimed design.
